UNITED STATES PATENT OFFICE

AXEL F. CARLSON, OF CAMBRIDGE, MASSACHUSETTS, ASSIGNOR TO THE REECE BUTTON HOLE MACHINE COMPANY, OF BOSTON, MASSACHUSETTS, A CORPORATION OF MAINE

SEWING MACHINE

Application filed May 29, 1926. Serial No. 112,507.

This invention relates to buttonhole sewing machines and particularly to the work clamp and novel means for closing the clamp onto the work and then spreading the clamp to place the cloth under slight tension while the buttonhole stitches are being formed, said means operating to contract the clamp and then to raise it at the end of the sewing operation.

10 In order to give an understanding of the invention I have illustrated in the drawings a selected embodiment thereof which will now be described after which the novel features will be pointed out in the appended 15 claims.

In the drawings, Fig. 1 is a side view of a sewing machine embodying my invention; Fig. 2 is a plan view of the work-supporting arm and work clamps thereon;

20 Fig. 3 is a side view of Fig. 2;

Fig. 4 is an enlarged section on the line 4—4, Fig. 1;

Fig. 5 is an enlarged section on the line 25 5—5, Fig. 2;

Fig. 6 is a fragmentary detail view showing the operation of the latch for holding the clamps open;

Fig. 7 is a section on the line 7—7, Fig. 5;

30 Fig. 8 is an enlarged section on the line 8—8, Fig. 1;

Fig. 9 is a section on substantially the line 9—9, Fig. 8;

Fig. 10 is an enlarged section on the line 35 10—10, Fig. 1.

The present invention is shown as embodied in a sewing machine similar to that illustrated in my co-pending application Serial No. 79,523, filed January 6th, 1926, 40 said machine being a two-thread button-hole sewing machine. This sewing machine has the frame 1 from which extends the usual overhanging arm 2 carrying the upper thread-manipulating mechanism comprising the usual needle 3 which is mounted in a vertically-reciprocating needle bar 4. The frame also has extending therefrom a lower work-supporting arm 5 on which the work *w* is supported, this work-supporting 45 arm 5 carrying the under thread-manipulating mechanism which may be of any ap-

proved type but which is not herein shown.

The operating mechanism is driven from a driving shaft 6 which in turn is actuated from a constantly-rotating driving pulley 7, the latter being driven by the driving belt 55 8. This driving pulley 7 is connected to and disconnected from the driving shaft 6 through the medium of a suitable clutch, (not shown) situated in a recess in the pulley 7, said clutch being controlled by a cone-shaped clutch actuator 9 which is slidably mounted on the shaft 6. Movement of the clutch actuator toward the left Fig. 8 throws the clutch into engagement and movement to the right into the position 60 shown in Figs. 8 and 10 releases the clutch.

This clutch actuator 9 is controlled by a clutch-controlling rod 10 which is slidably mounted in the frame and which has fast thereon a forked arm 11, the fork of which engages in a groove 12 in the clutch-controlling member 9 so that movement of the rod 10 in the direction of its length will throw the clutch into engagement or release the clutch. The clutch-actuating rod 10 is given its clutch-engaging movement by means of an elbow lever 13 pivoted to the frame at 14, the vertical arm 15 of said elbow lever engaging the end of the rod 10. When the horizontal arm of the lever 13 is pulled downwardly the elbow lever will be turned thereby shifting the rod 10 to the left Figs. 10 and 8 and throwing the clutch into engagement. When the clutch 70 is thus engaged the rod 10 is latched in its operative position by means of a latch 16 adapted to engage a notch 17 in the rod and when the latch is released the rod will be automatically shifted into a position to 75 disengage the clutch by means of a spring 18, all as shown in my above-mentioned application. It might be added here that suitable means, not shown, is provided for automatically releasing the latch 16 when the stitching on the buttonhole has been completed, all as shown in said co-pending application Serial No. 79,523.

The elbow lever 13 may be operated in any suitable way. It is herein shown as 80 having a link 19 pivotally connected to the 85

55

60

65

70

75

80

85

90

95

100

horizontal arm, which link is adapted to be actuated by a treadle or other starting mechanism. Said link is shown as extending through a head 20 fast on the end of a connection 21 that leads to a treadle or other starting device, said link 19 having a collar 22 thereon so that when the connection 21 and head 20 are moved downwardly the engagement of the head with the collar 22 will actuate the elbow lever 13.

The starting mechanism above described has also associated therewith a stopping mechanism for bringing the machine to rest. This stopping mechanism comprises a stop motion block 24 which is fast on the rod 10 and which carries a stop dog 25 that is adapted to co-operate with a stop cam 26 to stop the machine. This stop cam is fast on the shaft 6. When the rod 10 has been shifted to the left Figs. 10 and 8 to throw the clutch into engagement the stop dog 25 is in a position at one side of the path of travel of the stop cam. When, however, the latch 16 has been released at the end of the sewing operation the rod 10 will be shifted to the right by its spring 18 and this will bring the stop dog 25 into the path of movement of the stop cam and when during the rotation of the shaft the stop cam engages the stop dog the machine will be brought to rest, all as described in the above-mentioned application.

The work *w* is held by a suitable work holder comprising under clamps 27 and upper clamps 28. Both clamps are mounted on a work-supporting plate 29 which in turn is supported on the work-supporting arm 5, so that it can move longitudinally of the arm and also transversely thereof. The movement longitudinally of the arm is that which gives the work its feeding movement during the stitching along the side of the buttonhole and the movement transversely of the arm is that which gives the work a jogging movement for forming the barring stitches at the end of the buttonhole, all as usual in buttonhole sewing machines of this type.

The upper work clamps 28 are carried by arms 30 which extend from the upper end of a rocking member 31 that is pivoted on a shaft 32 carried by the clamp plate 29. These upper clamps are yieldingly held against the work by means of springs 33 which encircle pins 34 rising from the upper clamp arms 30. The upper ends of said pins 34 are guided in openings formed in the upper end of an upstanding arm 35 which is rigid with the clamping plate 29. These springs engage the arm 35 at one end and engage adjustable collars 36 on the pins at their lower ends.

The clamps are opened at the end of a stitching operation and are held open while the machine is at rest through the medium of a latch 37 and the following mechanism.

65 Mounted in bearings in the clamp plate 29 is

a rock shaft 38 having rigid therewith an offset crank 39 (see Figs. 2, 3 and 5,) the end of which crank engages the under side of an arm 40 fast on a rock shaft 41 that is journalled in a bearing on the under side of the rocking member 31 (see Fig. 5).

The arms 39 and 40 are tied together through the medium of a band 42 and the arm 40 is provided with laterally-extending pins 43 situated underneath the upper clamp arms 30. When, therefore, either of the shafts 38 or 41 are rocked the pins 43 will engage the under side of the clamp arms 30 and raise the clamps.

The shaft 38 has at its end an arm 44, said arm carrying a projection 45 adapted to be engaged by the latch 37. This latch not only holds the clamps open by its engagement with the projection 45 but also operates to lift the clamps at the end of the buttonhole by mechanism which will be presently described.

When the machine is first started the latch 37 is automatically released from the projection 45 as shown by dotted lines Fig. 1 thereby to allow the work clamps to close by the action of the springs 33. This release of the latch is accomplished by the following mechanism.

Pivoted to the bed frame is a swinging arm 46 carrying a pin 47 adapted to engage a cam surface 48 on the under side of the latch 37. This swinging arm or lever 46 is connected by a link 49 to an elbow lever 50, the latter having a depending rod 51 pivotally connected thereto which extends through the head 20. This rod 51 has a collar 52 thereon with which the head 20 engages so that downward movement of the starting treadle will operate through the connections above described to swing the lever 46 from the full to the dotted line position Fig. 1 during which movement the pin 47 will engage the cam surface 48 and thus raise the latch 37 and release it from the projection 45. As soon as the latch is released the springs 33 operate to close the clamps as will be readily understood. The collar 52 is adjusted so that on the initial downward movement of the head 20 the latch will be released while the collar 22 is so adjusted that the clutch will not be thrown until after the head has made its initial downward movement and the clamps are released.

The work clamps are so constructed that when they are closed onto the work they will be separated or spread thereby to put the cloth under slight tension while the buttonhole is being sewed. The construction is also such that when the clamps are raised they are automatically closed together or contracted again.

The rock shaft 41 carrying the lifting arm 40 has rigid therewith two heads 53 (see Fig. 4) each of which is formed with a cam groove 54 (see Fig. 2), and each clamp arm 30 is pro-

vided with a projection 55 which enters one of the cam grooves 54.

Means are provided whereby after the latch 37 has been released from the projection 45 and the clamps are closed onto the work the shaft 41 will be turned into the dotted line position Fig. 5 and during this turning movement the action of the cam grooves 54 will operate to spread the clamp arms 30, it being understood that said arms are pivoted at their rear ends as shown at 56. This turning movement of the shaft 41 to spread the clamps is derived positively from the swinging movement of the lever 46 by which the latch 15 is released. For this purpose said lever has rigid therewith an arm 57 which during the swinging movement of the lever 46 will engage a roll 58 on the end of the projection 45. The end of this lever 57 is cam shaped so that 20 the swinging movement of the lever into the dotted line position Fig. 1 will give a positive turning movement to the shaft 38 thus swinging the arm 39 downwardly and since said arm is tied to the arm 40 by the connection 42 this turning movement of the shaft 38 and arm 39 will be communicated to the arm 40 and the shaft 41.

The arm 57 is so positioned that it will not engage the roll 58 until after the latch 37 has 30 been released by the action of the pin 47 engaging the cam 48. Consequently the turning of the shaft 41 to spread the clamps does not occur until after the clamps are closed onto the work. The extent of this spreading movement is determined by a stop screw 76 which is carried by the part 31 and with which the tail 75 of the lever 40 is brought into engagement when the shaft 41 is given its turning movement. When the work clamps have been closed and spread the arms 39 and 40 are in the dotted line position Fig. 5 with the lifting pins 43 separated from the underside of the arms, in which position they remain until the clamps are opened again.

45 With this construction, therefore, when the head 20 is depressed the initial depressing movement will raise the latch 37 and release the work clamps allowing them to close and then further movement of the head will bring 50 the arm 57 into engagement with the projection 58 and thus spread the clamps and still further downward movement of the head will throw the clutch to set the sewing mechanism into operation. The spreading of the clamps, 55 therefore, does not occur until after they have been brought into contact with the work.

At the end of the sewing operation the clamps are automatically opened by means controlled by the stop mechanism.

60 The latch 37 is pivotally connected to a lever 59 which is mounted on a rock shaft 60 journalled in the frame, said rock shaft having another arm 61 connected thereto which is adapted to be actuated by a cam 62 journalled on a stud or shaft 63. This cam is nor-

mally at rest while the stitch-forming mechanism is in operation but is adapted to be clutched to a constantly-driven member 64 when the stop motion acts to bring the stitch-forming mechanism to rest. The constantly-driven member 64 is in the form of a gear loosely mounted on the stud 63 and meshing with a gear 65 which is connected to and actuated from the driving pulley 7. The cam 62 is automatically clutched to the constantly-driven member 64 through the medium of a clutch pin 66 in a manner similar to that shown in my co-pending application Serial No. 79,523, and also in a manner similar to that shown in the co-pending application of John Kiewicz, Serial No. 75,518, filed December 15th, 1925.

While the sewing operation is in progress the clutching pin 66 is withdrawn and is held withdrawn by the clutch dog 67. When the stop motion operates to bring the stitch-forming mechanism to rest the clutch dog 67 is released from the clutch pin 66 and the latter is thrown into clutching engagement with the constantly-rotating member 64 by means of a spring 68 thereby clutching the cam to the constantly-rotating member. To accomplish this the clutch dog is mounted on a rock shaft 69 which has an arm 70 rigid therewith, said arm carrying a projection 71 which is acted on by an arm 72 fast on the stop motion block 24. When the stop motion acts to bring the machine to rest the engagement of the stop cam 26 with the stop dog 25 will give the stop motion block a slight turning movement about the rod 10 so that the arm 72 will be moved momentarily into the dotted line position Fig. 9 thus engaging the projection 71 and turning the arm 70 and shaft 69. This slight turning movement of the shaft 69 is sufficient to raise the clutch dog 67 and release it from the clutch pin 66 thus allowing the clutch to become operative.

The clutch device by which the cam is clutched to the constantly-rotating member is a one-revolution clutch and after one complete revolution of the cam the clutch pin will be withdrawn from its operative position by the clutch dog 67.

When the cam 62 is at rest during the sewing operation the high part thereof engages the lever 61 thus holding the latch in its retracted position. As the cam starts rotation the high part passes out from under the arm 61 and the rock shaft 60 is turned through the medium of a spring 168 thereby moving the arm 59 toward the left Fig. 1 and projecting the latch 37 forwardly. In said Fig. 6 the arm 44 and projection 45 are in the position they assume when the clamps are closed, and the forward movement of the latch is sufficient so that it will drop over the projection 45, as shown by dotted lines Fig. 6. As the cam completes its rotation the high part thereof will engage the lever 61 thereby

70

75

80

85

90

95

100

105

110

115

120

125

130

- swinging the arm 59 to the right Fig. 1 and retracting the latch, said latch during its retracting movement swinging the arm 44 rearwardly and thus raising the clamps.
6. The cam 62 comes to rest in the position shown in Fig. 1 and the work clamps are thus held raised by the latch, said latch holding the clamps raised until the machine is started for the next stitching operation.
10. When the latch 37 is actuated to open the clamps as above described the initial retracting movement of the latch will swing the arms 39 and 40 upwardly from the dotted line position to the full line position Fig. 5 thereby to bring the pins 43 in engagement with the under side of the clamp arms. During this movement the shaft 41 and the heads 53 thereon are turned and operate to contract the clamps. Further retracting movement 20 of the latch will give the arm 44, shaft 38, arms 39 and 40 a further swinging movement which will operate to raise the clamps as will be readily understood.
25. I claim:
1. In a sewing machine, the combination with stitch-forming mechanism, of two work clamps for holding the work, a spring device for holding the clamps yieldingly against the work, a latch to hold the clamps raised when the machine is at rest, a swinging member operative during its initial movement to release the latch to allow the clamps to close and during its further movement to spread the clamps.
2. In a sewing machine, the combination with stitch-forming mechanism, of two work clamps, a spring device for holding the clamps yieldingly against the work, a latch to hold the clamps raised when the machine is at rest, a movable actuating member, and means operative during its initial movement to release the latch and during its further movement to spread the clamps.
40. 3. In a sewing machine, the combination with switch-forming mechanism, two work clamps, a spring for holding said clamps yieldingly against the work, a latch to hold the clamps raised, a cam device for spreading the clamps, and a movable actuating member operative during its initial movement to release the latch and during further movement to actuate the cam device to spread the clamps.
45. 4. In a sewing machine, the combination with stitch-forming mechanism, of a clutch for driving said mechanism, work clamps, a spring to hold the work clamps yieldingly against the work, a latch by which said work clamps are raised, an actuating device and connections whereby during the initial movement of the actuating device the latch will be released to allow the clamps to close and during further movement the clamps will be spread and during still further movement
- the clutch will be engaged to start the stitch-forming mechanism in operation.
5. In a sewing machine, the combination with stitch-forming mechanism, of a clutch for driving said mechanism, work clamps, a spring to hold the work clamps yieldingly against the work, a latch by which said work clamps are raised, an actuating device and connections whereby during the initial movement of the actuating device the latch will be released to allow the clamps to close and during further movement the clamps will be spread and during still further movement the clutch will be engaged to start the stitch-forming mechanism in operation, stopping mechanism to bring the machine to rest and means actuated by the stopping mechanism to raise the clamps when the stitch-forming mechanism has been brought to rest.
6. In a sewing machine, the combination with stitch-forming mechanism, of driving and stopping mechanism therefor, of two work clamps for holding the work, a spring to hold the clamps yieldingly against the work, a latch to hold the clamps raised when the machine is at rest, an actuating device operative during its initial movement to release the latch and during a further movement to spread the clamps, and means operated by the stopping mechanism to raise the clamps when the stitch-forming mechanism is brought to rest.
7. In a sewing machine, the combination with stitch-forming mechanism, of driving and stopping mechanism therefor, work-clamping means for holding the work, a spring to hold the clamping means yieldingly against the work, a rocking member for raising the clamps, a latch engaging said member for holding the clamping means raised, said latch being separate from the driving and stopping mechanism, a movable member which upon its initial movement releases the latch to allow the clamping means to close and upon further movement starts the driving mechanism in operation, and means actuated by the stopping mechanism when the stitch-forming mechanism is brought to rest to cause the latch to engage the rocking member and open the clamping means.
8. In a sewing machine, the combination with two work clamps each carried by an arm having a follower stud, a rocking member having two cam grooves, one for each follower stud, means to turn the rocking member just after the clamps are closed to spread the clamps, and a latch to turn the rocking member when the clamps are opened to contract the clamps.
9. In a sewing machine, the combination with two work clamps, an arm by which each clamp is supported, each arm having a follower stud, a shaft having two cam grooves, one for each follower stud, a spring device

for holding the work clamps yieldingly against the work, a latch for holding said clamps raised, a movable member operative during its initial movement to release the latch thereby allowing the clamps to close and during its further movement to turn the shaft thereby to spread the clamps.

10. In a sewing machine, the combination with stitch-forming mechanism, of driving and stopping mechanism therefor, work-clamping means, a spring device for holding the clamping means yieldingly against the work, a clamp-lifting member, a latch cooperating therewith to lift the clamping means and hold it raised, means to release the latch to allow the clamping means to close onto the work, a cam device which is normally stationary during the sewing operation, means actuated by the stopping mechanism in bringing the stitch-forming mechanism to rest to render said cam operative, and means actuated by the cam to manipulate the latch thereby to operate the clamp-lifting member and lift the clamping means.

25. 11. In a sewing machine, the combination with stitch-forming mechanism, of driving and stopping mechanism therefor, work clamps, a spring for holding said work clamps yieldingly against the work, a rotary cam device, a constantly-rotating member, means actuated by the driving and stopping mechanism in bringing the machine to rest to couple said cam device to the constantly-rotating member and then to release said cam device when it has made a complete rotation continuously, and means actuated by said cam device to raise the clamps.

12. In a sewing machine, the combination with stitch-forming mechanism, of driving and stopping mechanism therefor, a starting device by which the driving mechanism is set in operation, work clamps, a spring for holding said work clamps yieldingly against the work, a rotary cam device, a constantly-rotating member, means actuated by the driving and stopping mechanism in bringing the stitch-forming mechanism to rest to couple said cam device to the constantly-rotating member and then to release said cam device when it has reached a predetermined position, means actuated by said cam to raise the clamps, and means actuated by said starting device to release the clamps while the cam remains in such predetermined position.

55. 13. In a sewing machine, the combination with stitch-forming mechanism, of driving and stopping mechanism therefor, work clamps, a spring for holding said work clamps yieldingly against the work, a cam device, a constantly-rotating member, means actuated by the driving and stopping mechanism in bringing the stitch-forming mechanism to rest to couple said cam device to the constantly-rotating member, a clamp-raising latch, and means actuated by the cam device

to operate the latch thereby to raise the clamps.

14. In a sewing machine, the combination with stitch-forming mechanism, of driving and stopping mechanism therefor, work clamps, a spring for holding said clamps yieldingly against the work, a cam device, a constantly-rotating member, means actuated by the driving and stopping mechanism in bringing the stitch-forming mechanism to rest to couple said cam device to the constantly-rotating member and then to release said cam device when it has reached a predetermined position, a clamp-raising latch, and means actuated by the cam device to operate the latch and thereby raise the clamps.

15. In a sewing machine, the combination with stitch-forming mechanism, of driving and stopping mechanism therefor, work clamps, a spring for holding said clamps yieldingly against the work, a cam device, a constantly-rotating member, means actuated by the driving and stopping mechanism in bringing the stitch-forming mechanism to rest to couple said cam device to the constantly-rotating member and then to release said cam device when it has reached a predetermined position, a clamp-raising latch, means actuated by the cam device to operate the latch and thereby raise the clamps, and means to release the latch while the cam remains in such predetermined position.

16. In a sewing machine, the combination with stitch-forming mechanism, of driving and stopping mechanism therefor, two work clamps for holding the work, a spring device for holding the clamps yieldingly against the work, a rotary cam device, a constantly-rotating member, means actuated by the driving and stopping mechanism in bringing the stitch-forming mechanism to rest to couple said cam device to the constantly-rotating member, a clamp-raising latch, means actuated by said cam device to operate the latch and thereby raise the clamps, said latch holding the clamps raised while the machine is at rest, and means independent from the cam to release the latch to allow the clamps to close.

17. In a sewing machine, the combination with stitch-forming mechanism, of driving and stopping mechanism therefor, two work clamps for holding the work, a spring device for holding the clamps yieldingly against the work, a rotary cam device, a constantly-rotating member, means actuated by the driving and stopping mechanism in bringing the stitch-forming mechanism to rest to couple said cam device to the constantly-rotating member, a clamp-raising latch, means actuated by said cam device to operate the latch and thereby raise the clamps, said latch holding the clamps raised while the machine is at rest, a latch-releasing member independent from the cam, and means actuated there-

by to spread the clamps after they have closed.

18. In a sewing machine, the combination with stitch-forming mechanism, of driving and stopping mechanism therefor, two work clamps for holding the work, a spring device for holding the clamps yieldingly against the work, a rotary cam device, a constantly-rotating member, means actuated by the driving and stopping mechanism in bringing the stitch-forming mechanism to rest to couple said cam device to the constantly-rotating member, a clamp-raising latch, means actuated by said cam device to operate the latch and thereby raise the clamps, said latch holding the clamps raised while the machine is at rest, a latch-releasing member independent from said cam and operative during its initial movement to release the latch thereby to allow the clamps to close and during its further movement to spread the clamps.

19. In a sewing machine, the combination with stitch-forming mechanism, of driving and stopping mechanism therefor, two work clamps for holding the work, a spring device for holding the clamps yieldingly against the work, a rotary cam device, a constantly-rotating member, means actuated by the driving and stopping mechanism in bringing the stitch-forming mechanism to rest to couple said cam device to the constantly-rotating member, a clamp-raising latch, means actuated by said cam device to operate the latch and thereby raise the clamps, said latch holding the clamps raised while the machine is at rest, a cam device for spreading the clamps and a movable actuating member operative during its initial movement to release the latch and during further movement to actuate the cam device to spread the clamps.

20. In a sewing machine, the combination with stitch-forming mechanism, of driving and stopping mechanism therefor, two work clamps for holding the work, a spring device for holding the clamps yieldingly against the work, a rotary cam device, a constantly-rotating member, means actuated by the driving and stopping mechanism in bringing the stitch-forming mechanism to rest to couple said cam device to the constantly-rotating member, a clamp-raising latch, means actuated by said cam device to operate the latch and thereby raise the clamps, said latch holding the clamps raised while the machine is at rest, an actuating device and connections whereby during the initial movement of the actuating device the latch will be released to allow the clamps to close and during further movement the clamps will be spread and during still further movement the driving mechanism will be rendered operative to start the stitch-forming mechanism in operation.

21. In a sewing machine, the combination with stitch-forming mechanism, of driving and stopping mechanism therefor, work-

clamping means for holding the work, a spring to hold the clamping means yieldingly against the work, a latch for holding the clamping means raised against the action of the spring, a starting device by which the driving and stopping mechanism is set in operation to start the machine, latch-releasing means, connections between said starting device and both the latch-releasing means and the driving and stopping mechanism, the latter connections having a lost motion, whereby when the starting device is operated its initial movement will actuate the latch-releasing means thereby releasing the latch and allowing the clamping means to close against the work and subsequent movement will set the driving mechanism in operation.

In testimony whereof, I have signed my name to this specification.

AXEL F. CARLSON.
